HIDEICHI SAKURAI AND TARANO SAKURAI, OF SEATTLE, WASHINGTON.

KNITTING FRAME.

Application filed May 27, 1926. Serial No. 111,977.

This invention relates to frames upon which to fabricate knitted material, more particularly in the form of wales, from which sweaters, scarfs, hoods, etc., are produced.

The object of the invention, generally, is to provide an efficient frame of this character upon which the knotting and knitting of the yarn may be accomplished in a most convenient, rapid and uniform manner.

The invention is illustrated by the accompanying drawing, in which,—

Figure 1 is a perspective view of a device embodying our invention in its construction now preferred by us; Fig. 2 is a similar view of the same illustrating the device regulated to an adjustment different from that in which it is shown in Fig. 1; Fig. 3 is a similar view of a modified form of the device; and Fig. 4 is a fragmentary plan view of the device shown applied. Fig. 5 is a plan view showing portions of two wales, exemplifying a mode or manner of connecting the same together.

In the preferred form of the invention, shown in Figs. 1 and 2, the device consists of a substantially U-shaped frame member, the arm elements 10 being held parallel with each other by means of a regulating bar 14. As shown, said bar is provided with two pairs of notches 15—15 and 16—16, within which the frame-arms are engaged to retain the same at definite distances apart.

When the notches 15—15 are used, the arms will be held by the bar 14 parallel with each other as shown in Fig. 1; but when the notches 16—16 are used to receive the arms, a link 17 is sleeved upon the frame (Fig. 2) to cooperate with the bar for retaining the arms 10 in parallel at a shorter distance apart than when the notches 15—15 are used.

The bar 14 is connected to said frame member by the provision of a rod 12, one end of which is secured to the bar and its other end is formed with an eye 13 through which said member extends at the bend 11 thereof. The rod 12 is disposed medially of the arms 10 and constitute with the bar a part, or second member of the frame. The bar is located at a distance, approximately, of one-third the length of the device from the extremities of the arms.

The frame to the rear, or left hand side of the bar 14 in Figs. 1 and 2, of the device will be hereinafter designated as the handle

end and the arms which protrude beyond the bar, as the prongs.

In the modified construction, Fig. 3, the device is constructed of two side arms 10¹ and 10² having branches 18, 18¹ and bar elements 19, 19¹ extending at right angles therefrom; the branch and bar elements 18 and 19 of one arm 10¹ being tubular to receive therein the branch and bar elements 18¹ and 19¹, respectively, of the other arm 10², thereby permitting lateral adjustment of the two arms with respect to each other. 20 represents set screws extending through threaded holes in the parts 18, 19 and engaging the complementary branch 18¹ and bar part 19¹ for securing the members of the device at selected spaced apart relations with each other. For using the device, in either of its forms, the work, as a wale, is progressively produced by means of a knitting needle, of any known or suitable type, upon the prongs thereof as indicated in Fig. 4 in the following manner: One end of the yarn is secured as a loop *a* upon the prong *x* and then extended to the prong *y* about which the yarn is looped as indicated by *b*¹ and thence as in loops *c* and *b* about prongs *x* and *y* alternately. In passing the yarn from one prong to another the successive leads are knotted together in pairs, as indicated by *d*, the knots being of suitable shapes and sizes to conform with a desired pattern.

After the prongs are occupied their entire length, or nearly so, with the loops *b* and *c* of a wale, the same, when using the device as shown in Figs. 1 and 2, may be slid down upon the handle portions of the arms 10 by temporarily disengaging the bar 14 from the arms.

Two wales W and W¹, Fig. 5, are coupled together by passing a loop *b* of the wale W¹ through the loops *c* of the other wale W, then this loop *c* through the next loop *b* of wale W¹, and so on, one loop with another.

The wales may be arranged in any desired manner to produce different articles which are characterized by ridges at the loop connections.

A device constructed according to the present invention, not only facilitates the work but enables persons, whether skilled or not, to produce uniform and attractive looking knitted products.

While we have shown and described the

invention with respect to two forms of construction, we do not wish to be understood as confining ourselves thereto except as limited by the scope of the following claims.

5. What we claim, is,—

1. A knitting device comprising a frame having a substantially U-shaped member, and a bar member, said bar member being provided with notches to receive the arms 10 of the first named member to retain said arms in parallel relation at a definite distance apart, said bar being located intermediate the length of the frame, and a rod extending from said bar and connected to the 15 U-shaped member at the bend thereof.

2. A knitting device comprising a frame having a substantially U-shaped member, a bar member located intermediate the 20 length thereof and connected to said arms to retain the same parallel with each other, and a rod rigidly secured at one end thereof to said bar and connected at its other end

to the first named member at the bend thereof.

3. A knitting device having a frame member of a substantially U-shape to provide two side arms, a transversely arranged bar detachably connected to said arms intermediate the length of the same to afford prong elements at one side of the bar, and a rod between said arms and entirely at the other side of the bar from the prongs, said rod having its ends permanently connected to the said frame member and the bar respectively and permitting the bar to be disengaged from said arms to permit the work being shifted on the arms from the prong ends thereof to beyond the position whereat the bar engages the arms.

Signed at Seattle, Washington, this 13th 40 day of April, 1926.
